SQUEEGEE

Earl S. Neal, San Francisco, Calif.
(2600 El Camino Real, San Mateo, Calif.)
Filed Apr. 26, 1962, Ser. No. 190,485
10 Claims. (Cl. 15—245)

This invention relates to new and useful improvements in squeegees, particularly although by no means necessarily, for removing water, etc. from floors, pavements and other surfaces which have been hosed down, and has for its primary object to provide, in a manner as hereinafter set forth, an implement of this character which is adapted to be used with either a push or pull stroke.

Another important object of the present invention is to provide an improved reversible squeegee of the aforementioned character comprising unique means for retaining the blade in the selected functioning position.

Still another important object of the invention is to provide a squeegee of the character described wherein the blade may be expeditiously set or adjusted for push or pull operation without being touched with the hands of the user and while in a standing position.

Another object of the present invention is to provide a squeegee of the character set forth comprising novel means for mounting the blade for oscillation on the head assembly.

Other objects of the invention are to provide a reversible squeegee which is comparatively simple in construction, strong, durable, compact, of light weight and which may be manufactured at low cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of a reversible squeegee constructed in accordance with the present invention;

FIGURE 2 is a view in side elevation of the device, showing the blade in the pull position;

FIGURE 3 is a side elevational view, showing the blade in intermediate position as when being swung from the pull to the push position;

FIGURE 4 is a side elevational view, showing the blade in push position;

FIGURE 5 is a bottom plan view of the device with portions broken away;

FIGURE 6 is a vertical sectional view, taken substantially on the line 6—6 of FIGURE 5;

FIGURE 7 is a view principally in vertical section through one end portion of the device, taken substantially on the line 7—7 of FIGURE 6;

FIGURE 8 is a fragmentary view on an enlarged scale, taken substantially on the line 8—8 of FIGURE 5; and

FIGURE 9 is an exploded perspective view of the blade supporting means on one end portion of the device.

Referring now to the drawing in detail, it will be seen that the embodiment of the present invention which has been illustrated comprises an elongated handle 10 of wood or other suitable material. The handle 10 may also be of any desired length and diameter. Mounted on the forward end portion of the handle 10 is a head assembly which is designated generally by reference numeral 11.

The head assembly 11 includes a cylindrical crosshead 12 which is fixedly mounted on the forward end portion of the handle 10. Toward this end the crosshead 12 includes at an intermediate point a radial socket 13 which receives the handle 10. Mounted on the end portions of the crosshead 12 is a pair of brackets 14 of suit-

2

able metal or other material. The brackets 14 include generally U-shaped clips or yokes 15 comprising flat bight portions 16 and inwardly offset legs or end portions 17 of arcuate cross-section which straddle the end portions of the crosshead 12 and conform to the periphery thereof. The end portions or legs 17 of the members 15 are apertured as indicated at 18 to receive screws 19 for securing the brackets 14 on the crosshead 12. Fixedly secured as by rivets 20 on the flat bight portions 16 of the members 15 are vertical channel bars 21. The bars 21 extend below the clips or yokes 15 and are provided with openings 22 in their lower end portions. Openings 23 in the bars 21 accommodate the rivets 20. The side flanges 24 of the bars 21 terminate short of the lower ends of said bars. At the upper ends thereof the bars 21 terminate in outturned apertured ears or the like 25.

Mounted beneath the crosshead 12 in spaced parallelism therewith is a rod or shaft 26 the end portions of which are journaled in the openings 22 in the lower end portions of the bars 21. Mounted on the shaft 26 is a generally U-shaped clamp 27 of sheet metal or other suitable material. The bight portion 28 of the clamp 27 is shaped to accommodate the shaft 26 and is secured thereon by a pin 29. As shown to advantage in FIGURE 8 of the drawing, from the shaft 26 the sides or jaws 30 of the clamp 27 converge and contact each other, as indicated at 31. Mounted between the sides or jaws 30 of the clamp 27 and protruding therefrom is a blade 32 of rubber or other suitable resilient material. Fastening elements 33 secure the blade 32 in position. Coil springs 34 have one end connected to the apertured ears 25 on the upper ends of the bars 21. The other ends of the coil springs 34 are connected to apertured lugs or ears 35 which project laterally from the clamp 27 adjacent the blade 32. Mounted on the crosshead 12, adjacent the ends thereof, are pairs of downwardly divergent stops 36 for the clamp 27. The stops 36 include angularly extending, arcuate inner end portions 37 which are apertured to accommodate securing screws 38.

It is thought that the use or operation of the implement will be readily apparent from a consideration of the foregoing. Briefly, when it is desired to use the device with a pulling stroke the blade assembly comprising the members 27 and 32 is swung to the position shown in FIGURES 1 and 2 of the drawing, in which position said blade assembly extends at a forward and downward inclination from the crosshead 12. When it is desired to convert to a pushing operation the blade assembly is swung through the intermediate position of FIGURE 3 of the drawing to the position shown in FIGURE 4 of said drawing, in which position said blade assembly extends at a rearward and downward inclination from the crosshead 12. In both positions the blade assembly trails the crosshead 12 in the operating stroke of the implement. The construction and arrangement is such that the coil springs 34 swing the blade assembly past dead center with a snap action and retain said blade in either position against the respective front and rear stops 36. The construction and arrangement also is such that the conversion may be quickly accomplished from a standing position by simply placing a foot, as indicated at 39 in FIGURE 3 of the drawing, in front or in back of the blade assembly. When the foot is so positioned it acts as a stop against which the blade assembly is engaged for causing said blade to swing to the opposite position.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and

equivalents may be resorted to, falling within the scope of the invention as claimed.

What is claimed as new is as follows:

1. A reversible squeegee comprising, a handle, a blade pivotally mounted for oscillation between two optional operative positions on the handle, and resilient means for snapping the blade past dead center and yieldingly retaining same in the selected operative position when said blade is swung from either position to the other.

2. A reversible squeegee comprising a handle, a blade pivotally mounted for oscillation between two optional operative positions on the handle, and resilient means for snapping the blade past dead center and yieldingly retaining same in the selected operative position when said blade is swung from either position to the other, said means including at least one coil spring connected under tension to the handle and the blade on opposite sides of the pivotal axis of said blade.

3. The combination of claim 2, together with stops on the handle for arresting the swinging movement of the blade under the influence of said spring in the operative positions.

4. A reversible squeegee comprising an elongated handle, a cross head on one end of said handle, a blade pivotally mounted for oscillation between two optional operative positions on the crosshead in parallelism therewith, and tensioned coil springs connected to the end portions of the crosshead and to the blade on opposite sides of the pivotal axis of the latter for snapping said blade past dead center and yieldingly retaining same in the selected operative position when said blade is swung from either position to the other.

5. The combination of claim 4, together with means for arresting the swinging movement of the blade under the influence of the springs in said operative positions.

6. The combination of claim 5, said means including downwardly divergent stops mounted on the crosshead on opposite sides of the blade for engagement thereby.

7. A reversible squeegee comprising an elongated handle, a crosshead on one end portion of said handle, verti-

cal bars on the ends of the crosshead, a blade pivotally mounted for oscillation between the lower end portions of the bars, and tensioned coil springs connected to the upper portions of the bars and to the blade for snapping said blade past dead center and yieldingly retaining same in the selected operative position when said blade is swung from either position to the other.

8. The combination of claim 7, together with stops on the crosshead with the blade operable therebetween and engageable therewith to be arrested thereby in said operative positions.

9. A reversible squeegee in accordance with claim 7, said blade including a clamp of generally U-shaped cross-section providing a bight portion and a pair of opposed jaws, a shaft mounted in said bight portion and having its end portions journaled in the bars, and a resilient strip secured between the jaws and including a protruding longitudinal marginal portion.

10. A reversible squeegee comprising an elongated handle, a cylindrical crosshead on one end of said handle, generally U-shaped clips mounted longitudinally on the end portions of the crosshead, vertical bars mounted on the bight portions of said clips and extending upwardly and downwardly therefrom, a shaft journaled in the lower end portions of the bars and paralleling the crosshead, a clamp of generally U-shaped cross-section receiving the shaft in its bight portion for mounting said clamp on said shaft, a resilient wiper blade mounted in the clamp, tensioned coil springs connected to the upper end portions of the bars and to the clamp for snapping the blade past dead center when said blade is swung toward either of two optional operative positions and for yieldingly retaining said blade in said positions, and stops for the blade mounted on the crosshead on opposite sides of the clamp for engagement thereby.
